UNITED STATES PATENT OFFICE.

BENJAMIN F. HUTCHES, JR., OF NEW YORK, N. Y.

AUTOMATIC PAPER-FEEDER FOR TYPE-WRITERS.

No. 848,654.

Specification of Letters Patent.

Patented April 2, 1907.

Application filed February 26, 1906. Serial No. 302,902.

To all whom it may concern:

Be it known that I, BENJAMIN F. HUTCHES, Jr., a citizen of the United States, residing at New York city, Manhattan, county and State of New York, have invented new and useful Improvements in Automatic Paper-Feeders for Type-Writers, of which the following is a specification.

This invention relates to means for removing the old sheet and feeding a new sheet to a type-writer when the writing on the old sheet has been finished. The sheet-feeding mechanism is actuated by a key upon the depression of which the old sheet is removed and a new sheet is drawn out of a magazine and properly positioned upon the platen. This key is preferably not connected to the type-writer frame itself, but to a separate type-writer operator—such, for instance, as described in an application for a patent filed by me May 15, 1905, under Serial No. 260,413.

This operator when coupled to a type-writer produces simultaneously with the writing a perforated record thereof, so that when the record is subsequently fed through the operator such writing may be multiplied any desired number of times. The operator according to the present invention is provided with a paper-feed key which is to be depressed by the manipulator at the end of the writing when the operator is worked manually. This depression of the paper-feed key will cause the old sheet to be ejected from the type-writer, a new sheet to be introduced, and also a feed-perforation to be punched into the record. When subsequently the operator is actuated by such record, this perforation will serve to automatically actuate the paper-feeding mechanism at the end of each writing. Consequently the machine will now produce automatically copies of the writing for as long a time as it is allowed to run and without requiring the services of an attendant for renewing the sheets.

In the accompanying drawings, Figure 1 is a vertical section, partly in elevation, of my improved paper-feeder for type-writers; Fig. 2, a cross-section, partly broken away, through the magazine and adjoining parts; Fig. 3, a plan, partly in section, of the coupling; Fig. 4, a side view of the coupling, showing the pinion-wire and slide in section; Fig. 5, a plan of the head engaging the platen; Fig. 6, a side view thereof; Fig. 7, a side view

of part of the type-writer operator; Fig. 8, a plan thereof, partly broken away and with some of the parts omitted; Fig. 9, a vertical section on line 9 9, Fig. 8; Fig. 10, a plan of part of the grooved roller; Fig. 11, a plan of part of the record, and Fig. 12, a diagram showing the electric circuit that controls the coupling.

The letter *a* indicates the casing of a type-writer operator, which is separate from and adapted to support the type-writer *b*. The latter is provided with the usual reciprocating carriage *b'*, in which the printing roller or platen *b²* is rotatably mounted. The means for automatically turning the platen for one or more line-spaces are not shown and do not form part of this invention. Means, hereinafter described, are, however, shown for imparting a turn to platen *b²* when a written sheet is to be removed and replaced by a blank sheet. For this purpose I mount in carriage *b'* a feed-roller *c*, which is arranged parallel and in proximity to platen *b²*. Roller *c* is rotated from the latter by frictional contact, which contact may be increased by providing roller *c* with a covering *c'* of rubber or other resilient material. Above roller *c* there is secured to carriage *b'* by brackets *b³* a magazine *D*, containing a stack of blank sheets *A*. Magazine *D* is composed of an inclined bottom *d*, side walls *d'* *d''*, and front and rear walls *d³* *d⁴*. The magazine is so arranged that the edge formed between bottom *d* and front wall *d³* is located vertically above the axis of roller *c*. Along such edge I provide bottom *d* with a longitudinal slot *d⁵*, while a guard *d⁶*, curved concentrically to roller *c*, extends forward from wall *d³* and partially around roller *c*. The parts are so assembled that a small passage remains between roller *c* and guard *d⁶* of a height to accommodate a single sheet *A*. The bottom sheet *A'* of the stack rests with its front portion upon the roller *c* and the sheet will thus be taken along by such roller when the latter is rotated. From roller *c* the sheet *A'* is wound partly upon platen *b²*, to which it is held by bands *b⁴*. To set the magazine to sheets *A* of different widths, it is provided with a movable transverse partition *d'*, adjustable by screws *d⁸*.

Upon the completion of a writing a turn is given to platen *b²* by the means hereinafter described for the purpose of ejecting the old sheet and introducing a new sheet. These

means are as follows: In frame *a* of the type-writer operator is journaled a power-shaft *e*, which receives continuous rotation from an electromotor or other source of power. (Not 5 shown.) Upon shaft *e* is loosely mounted a worm-wheel *e'* in permanent engagement with an elongated toothed wheel or pinion-wire *f*. The gudgeons of the latter are hung in bearings *g'* of a slide *g*, which is U-shaped 10 in cross-section, Figs. 1 and 4. One end of pinion-wire *f* is provided with a bevel-gear *f'*, engaging a wheel *h'* of a spindle *h*, inclosed in a casing *g''*, forming part of slide *g*. Spindle *h* is intergeared by wheels *h''* *i'* with a 15 spindle *i*, rotatably mounted in bearing *g''* of casing *g''*. To spindle *i* is secured a ratchet-wheel *i''*, engaged by a resilient finger *i''*, which is fastened to a perforated head *i''*, loosely mounted upon spindle *i*. The enlarged end *i''* of head *i''* is provided with a recess *i''*, adapted to receive the usual knob or handle *b''* of platen *b''*, which is secured to head *i''* by clamp-screws *i''*. In this way the 20 slide *g* is connected to platen *b''*, and consequently to carriage *b'*, so as to be taken along by the same. The length of pinion-wire *f* is such that it will be engaged by wheel *e'* in all 25 positions of carriage *b'*. It will be seen that by rotating worm-wheel *e'* (which is adapted to be coupled to power-shaft *e* in manner hereinafter described) platen *b''* will also be 30 rotated by transmission *f*, *f'*, *h'*, *h*, *h''*, *i'*, *i*, *i''*, *i''*, and *i''*. The ratchet connection between head *i''* and spindle *i* permits the platen *b''* to 35 be rotated independently from the above-described mechanism at the commencement of each new line of the writing.

The means for coupling worm-wheel *e'* to shaft *e* are as follows: The hub *e''* of wheel *e'* 40 is notched, as at *e''*, to form one member of a clutch or coupling, the other member of which consists of a correspondingly-notched tube *e''*, slidably mounted on shaft *e*. Tube *e''* participates in the rotation of shaft *e* by a 45 pin *e''* on the tube engaging a slot *e''* of the shaft. Coupling member *e''* is further provided with a groove *e''*, engaged by the forked end *j'* of a spring *j*, secured to frame *a* by post *j''*. The fork *j'* rests against the armature *k'* 50 of an electromagnet *k*, which armature is secured to one pole of the electromagnet by a flexible metal strap *k''*, while its free end is normally held away from the electromagnet by spring *j*. If a current is sent through electromagnet *k* in manner hereinafter described, the latter will attract armature *k'* to close the coupling *e''* *e''*, so that worm-wheel *e'* will rotate together with power-shaft *e*, and thus 55 operate the platen, as already described.

60 The circuit may be closed either manually by a key or automatically by a perforated record fed through the type-writer operator and designed not only to introduce a new sheet, but also to actuate the character and shift 65 keys of the type-writer.

The construction is such that when the operator is worked by hand a record *m* is simultaneously formed by a set of punches with which the operator is provided. These punches are actuated by a series of keys *l* on 70 the operator, which also serve to work the corresponding keys of the type-writer and do not form part of the present invention. In addition to keys *l* there is pivoted to the operator-frame *a* at *l'* an additional key *l''*, 75 which I term the "paper-feed" key. This key when depressed will cause three separate operations to be performed—i. e., it will, firstly, cause the record to be advanced; secondly, the record to be punched, and, thirdly, 80 an electric circuit to be closed, so as to energize electromagnet *k* for operating the paper-feeding device. The record *m*, hereinabove referred to, passes first underneath a record-feed roller *n*, then partly around a 85 grooved roller *o*, and finally back over feed-roller *n*. The rollers *n* and *o* are rotatably mounted in a block *a'*, forming part of the operator-frame *a*. Above the roller *n* is arranged a rubber-covered pressure-roller *n'*, so 90 that the record when passing between rollers *n* *n'* will be positively taken along. For operating the feed-roller *n* I provide a swinging cross-bar *p*, hung in a pair of levers *p'* and arranged directly beneath keys *l* *l''* of the operator. The levers *p'* are pivoted to the operator-frame *a* at *p''* and are located at both sides of such frame, (only one lever being shown in the drawings.) Upon bar *p* is loosely mounted a pawl *q*, engaging by inclined nose *q'* a ratchet-wheel *n''*, fast on shaft *n''* of roller *n*. It will be seen that by depressing key *l* bar *p*, together with pawl *q*, will be lowered to turn ratchet-wheel *n''* and feed-roller *n*. After the nose *q'* has thus 105 turned wheel *n''* for the distance of one tooth *n''* it will be pushed out of engagement with wheel *n''* by the point of the next tooth *n''*. Thus the wheel *n''*, and consequently record *m*, will be arrested, while key *l''* may be still 110 further depressed. This further descent of key *l''* causes the record *m* to be punched in the following manner:

Block *a'* is perforated, as at *a''*, to accommodate a punch *r*, having a head *r'*. The punch *r* is located beneath key *l''* and is depressed by the last portion of the down-stroke of the key, so as to form the desired hole in the record. The punch is normally held in its raised position by a spring *r''*, engaging its head *r'* and secured to block *a'*.

To operate the paper-feed, spring *r''* extends beyond punch *r* to form a contact *r''*, arranged above a second contact *s*, insulated from block *a'*, as at *s'*. The rear end of contact *s* is secured to a contact-piece *t*, carried by block *a'* and insulated therefrom, as at *t'*. A wire *u*, connected to contact-piece *t*, leads to one pole of electromagnet *k*, the other pole of which is connected by wire *u'* 130

to a battery or other source of electricity U. The latter is in turn connected by a wire u^2 to block a' . The depression of key l^2 will thus close contacts r^3 s of a circuit, the current flowing as follows: from source of electricity U through wire u^2 , block a' , spring r^2 , contacts r^3 s, contact-piece t , wire u , electromagnet k , and wire u' back to source U. The electromagnet k has thus been energized 10 to attract armature k' , and thereby close coupling e^2 e^4 . In this way worm-wheel e' will be rotated to correspondingly turn platen b^2 in manner hereinbefore described, and thus feed the paper. Upon the release of 15 key l^2 pawl q and punch r will be raised, while contact r^3 s will be opened. Thus electromagnet k is deenergized to permit spring j to open coupling e^2 e^4 , and thereby arrest the platen b^2 . 20 If it is desired to multiply the copies of the writing, the record produced as described is repeatedly run through the type-writer operator by suitable means. (Not shown.) When the record is thus run through, it will 25 automatically feed the paper in the following manner: To block a' is pivoted at v' a lever v , having a pin v^2 and a contact v^3 . Finger v^2 is located above grooved roller o , while contact v^3 is located above contact-piece t . 30 The first groove o' of roller o is in alinement with the perforations m' of record m , so that when either of such perforations arrives beneath pin v^2 the lever v will drop until contact v^3 rests upon contact-piece t . In this 35 way a circuit is closed, the current flowing as follows: from source of electricity U through wire u^2 , block a' , lever v , contacts v^3 t , wire u , electromagnet k , and wire u' back to source U. In this way electromagnet k is 40 energized to close coupling e^2 e^4 , and thus start the paper-feed mechanism.

To adapt the feed mechanism to papers having differently-sized head-spaces, the holes m' of record m may be made of different 45 lengths, as illustrated in Fig. 11. If a large hole passes underneath pin v^2 , the feed device will be rotated for a longer period of time than when a short perforation passes underneath the pin, so that in this way the 50 feeding period is easily controlled by the length of the perforation.

It will be seen that by my invention the record may be properly punched at the end of a writing to form a feed-perforation and 55 that such perforation subsequently serves to automatically eject the old sheet and feed a new sheet to the machine upon the completion of each writing. In this way the operation is entirely automatic and writings may 60 be multiplied without requiring the service of an attendant for changing the sheets.

What I claim is—

1. A paper-feeder for type-writers comprising a reciprocating carriage, a paper-feed 65 roller journaled therein, a slide taken along

by the carriage, and means on the slide for rotating the feed-roller, substantially as specified.

2. A paper-feeder for type-writers comprising a reciprocating carriage, a paper-feed 70 roller and an adjoining platen journaled therein, a slide taken along by the carriage, and means on the slide for rotating the platen, substantially as specified.

3. A paper-feeder for type-writers comprising a reciprocating carriage, a paper-feed 75 roller journaled therein, a slide taken along by the carriage, a power-shaft, and means carried by the slide for rotatably connecting said shaft to the feed-roller, substantially as 80 specified.

4. A paper-feeder for type-writers comprising a reciprocating carriage, a paper-feed 85 roller journaled therein, a slide taken along by the carriage, means on the carriage for rotating the feed-roller, a power-shaft, and key-controlled means for rotatively connecting said shaft to the roller-rotating means on the carriage, substantially as specified.

5. A paper-feeder for type-writers comprising a carriage, a paper-feed roller journaled therein, a slide operatively connected to the carriage, means on the carriage for rotating the feed-roller, a power-shaft, a key-controlled clutch, and means controlled by 95 the clutch for operatively connecting said shaft to the roller-rotating means on the carriage, substantially as specified.

6. A paper-feeder for type-writers comprising a reciprocating carriage, a paper-feed 100 roller and an adjoining platen journaled therein, a slide taken along by the carriage, a power-shaft, and means carried by the slide for rotatably connecting said shaft to the platen, substantially as specified.

7. A paper-feeder for type-writers, comprising a platen, a feed-roller, a magazine, a head engaging the platen, a resilient finger on the head, a ratchet-wheel engaged by the finger, and means for rotating the ratchet-wheel, substantially as specified. 110

8. A paper-feeder for type-writers provided with a carriage, a platen journaled therein, a slide, means for coupling the slide to the platen, a pinion-wire journaled in the 115 slide, means for operatively connecting said wire to the platen, and a worm-wheel engaging the pinion-wire, substantially as specified.

9. A paper-feeder for type-writers provided with a carriage, a platen journaled therein, a slide, means for coupling the slide to the platen, a pinion-wire journaled in the 120 slide, means for operatively connecting said wire to the platen, a worm-wheel engaging the pinion-wire, a power-shaft, and means for coupling the worm-wheel to said shaft, substantially as specified.

10. A paper-feeder for type-writers provided with a carriage, a platen journaled 125

therein, a slide, means for coupling the slide to the platen, a pinion-wire journaled in the slide, means for operatively connecting said wire to the platen, a worm-wheel engaging the pinion-wire, a power-shaft, a clutch for coupling the worm-wheel to said shaft, a key, and means controlled by the key for operating the clutch, substantially as specified.

11. A paper-feeder for type-writers provided with a carriage, a platen journaled therein, a slide, means for coupling the slide to the platen, a pinion-wire journaled in the slide, means for operatively connecting said wire to the platen, a worm-wheel engaging the pinion-wire, a power-shaft, a clutch for coupling the worm-wheel to said shaft, a record, and means controlled by the record for operating the clutch, substantially as specified.

12. A paper-feeder for type-writers provided with a carriage, a platen journaled therein, a slide, means for coupling the slide to the platen, a pinion-wire journaled in the slide, means for operatively connecting said wire to the platen, a worm-wheel engaging

the pinion-wire, a power-shaft, a clutch for coupling the worm-wheel to said shaft, an electromagnet for operating the clutch, a key, and means controlled by the key for closing the circuit of the electromagnet, substantially as specified.

13. A paper-feeder for type-writers provided with a carriage, a platen journaled therein, a slide, means for coupling the slide to the platen, a pinion-wire journaled in the slide, means for operatively connecting said wire to the platen, a worm-wheel engaging the pinion-wire, a power-shaft, a clutch for coupling the worm-wheel to said shaft, an electromagnet for operating the clutch, a record, and means controlled by the record for closing the circuit of the electromagnet, substantially as specified.

Signed by me at New York city, Manhattan, New York, this 24th day of February, 1906.
